JOHN D. SCHWEERS, OF ELIZABETH, NEW JERSEY.

VALVE FOR INTERNAL-COMBUSTION ENGINES.

1,400,006.

Specification of Letters Patent. Patented Dec. 13, 1921.

Application filed August 25, 1920. Serial No. 405,960.

To all whom it may concern:

Be it known that I, JOHN D. SCHWEERS, a citizen of the United States, and a resident of Elizabeth, county of Union, and State of New Jersey, have invented certain new and useful Improvements in Valves for Internal-Combustion Engines, of which the following is a specification.

This invention relates to a valve for internal combustion engines and is of the type that is used for admitting an explosive mixture to the cylinders, and is primarily designed to eliminate the necessity of frequent grinding and cleaning now necessary in valves of the common type.

This invention relates to a valve of this kind in which the valve head is rotatable so that vibration of the engine in the quick rotation of the valve has a tendency to turn it slightly on each stroke, so that a rotative contact between the valve and its seat is established every time the valve is closed, this contact causing a continual slight grinding of the valve and its seat.

The invention further consists of a valve of this kind, the head of which can be provided with a conformation, preferably on the bottom, that permits the fluid under pressure, such as the compressed explosive mixture, engaging the valve, to positively rotate it through a partial rotation whenever such gases are permitted to go through the passage in the valve seat by the opening of the valve.

The invention is illustrated in the accompanying drawing, in which one form of the improved type of valve is shown, and in which drawing Figure 1 is an elevation of a valve with the valve seat shown in section, and Fig. 2 is a bottom view of the valve seat.

The valve is arranged usually in the inlet port or exhaust port of the cylinder, part of which cylinder is shown in elevation at 10, and is provided with a valve seat 11, these being shown tapered. The valve stem 12 is reciprocated by any of the means usually employed and is ordinarily held down by a spring, which is not shown, the function and location of which are well known and need not be described here.

On the valve stem is a valve head 13 which is held against appreciable movement longitudinally of the valve stem 12, but fits on the stem loose enough to permit the valve head to be rotated, this fit also pro-

viding a gas-tight joint, especially in conjunction with the head 14 on the valve stem, which head 14 also acts to limit the upward movement of the valve head relative to the stem, so that when the stem is pushed down it holds the valve head in position on the valve seat.

Suitable means for preventing downward movement of the valve head relative to the stem is provided, the form shown comprising a collar 15 which is held in position by suitable means, such as the pin 16, and the valve head is preferably provided with a sleeve 17 which rests against the collar 15. It will be noted that if the engine, especially the type used on vehicles, is running, vibration is established which will cause the head to be vibrated sufficiently to rotate it slightly between the time the valve head leaves the seat and the time it returns to its closed position.

If desired, I may construct the valve head so that it is positively rotated through the influence of compressed fluid, such as compressed gases, passing through the opening or passage in the valve seat when the valve is open. In the form shown this comprises obliquely arranged grooves 18 arranged on the bottom face 19 of the valve head, the spaces between these grooves thus forming vanes 20, and it will be readily seen that the passage of such fluids under pressure along these grooves will rotate the valve head.

The duration of time that the valve is open is slight, so that but a slight rotation will take place on each stroke of the valve, and each time the valve head is seated it will be in a different position relative to the position previously occupied, so that the surface of the valve, where it engages the seat, and the surface of the seat itself, will be kept clean and smooth and give no chance for the lodging of corroding or similar material on either one of these contacting elements, since the obliquely arranged grooves direct an oblique blast on these surfaces.

To permit an easier access of the fluid under pressure to the grooves 18 I prefer to place an annular groove 21 on the bottom face of the valve head, thus insuring the entrance of such fluid to the grooves and permitting it to exert a pressure along their entire lengths. Such fluid, in the way of an explosive mixture, will also be more thoroughly mixed by its being slightly swirled in performing the rotative function.

It will be understood that slight changes can be made in the details of the parts without departing from the scope of the invention.

5 I claim:

A valve for internal combustion engines comprising a stem, a valve head rotatably secured on the end of the stem, the valve head having a tapered edge and adapted to rest on a tapered valve seat, said valve head having an annular groove on its bottom face

adjacent said sleeve, and having obliquely arranged grooves extending from said annular groove to the tapered edge, whereby fluid under pressure traverses the grooves to give rotative movement to the head and to direct an oblique blast on the tapered face of the valve seat.

In testimony that I claim the foregoing, I have hereto set my hand, this 21st day of 15 August, 1920.

JOHN D. SCHWEERS.
